DESIGN FOR A SIGN

Rea M. Bruner, Houston, Tex., assignor of one-third to R. A. Kenley and Allan Murphy, both of Houston, Tex.

Application April 26, 1939, Serial No. 84,578

Term of patent 14 years

To all whom it may concern:

Be it known that I, Rea M. Bruner, a citizen of the United States, residing at Houston, in the county of Harris and State of Texas, have invented a new, original, and ornamental Design for a Sign, of which the following is a specification, reference being had to the accompanying drawing, forming part thereof.

In the drawing:

Fig. 1 is a perspective view of a sign showing my new design.

Fig. 2 is a front elevational view of the sign shown in Fig. 1.

Fig. 3 is a side elevational view thereof.

I claim:

The ornamental design for a sign, as shown.

REA M. BRUNER.
